UNITED STATES PATENT OFFICE.

CHARLES MALLINSON, OF LIVERPOOL, ENGLAND.

APPARATUS FOR CONDITIONING OR DRYING GRAIN.

SPECIFICATION forming part of Letters Patent No. 451,306, dated April 28, 1891.

Application filed October 24, 1890. Serial No. 369,211. (No model.) Patented in England October 2, 1888, No. 14,182, and July 11, 1890, No. 10,810; in France February 18, 1889, No. 196,140, and in Austria-Hungary September 11, 1889, No. 17,677 and No. 29,496.

To all whom it may concern:

Be it known that I, CHARLES MALLINSON, mill manager, a subject of the Queen of Great Britain, residing at Liverpool, in the county 5 of Lancaster, in the Kingdom of England, have invented certain new and useful Improvements in Apparatus for Conditioning or Drying Grain, (for which I have received Letters Patent in England, No. 14,182, dated 10 October 2, 1888, and No. 10,810, dated July 11, 1890; in France No. 196,140, dated February 18, 1889, and in Austria-Hungary, No. 17,677 and No. 29,496, dated September 11, 1889,) of which the following is a specification.

15 This invention relates to apparatus for drying granular or pulverulent material.

The primary object of the invention is an apparatus which will rapidly dry grain or similar produce in quantity.

20 The apparatus consists, briefly, of a zigzag casing, down which the material to be desiccated falls by gravity in one or more thin streams or layers, and within which a series of steam or hot-water pipes is arranged in 25 such manner that the descending stream of material is brought into very intimate contact with their heated surfaces. Suitable arrangements are also provided for admitting air to the casing, for drawing off the moisture 30 therefrom, and for breaking up the stream of material as it descends therein. Suitable feed and discharge devices are also provided.

In the drawings, Figure 1 is a general side elevation of the apparatus, parts being in section. Fig. 2 is a rear elevation of the apparatus, with part in section. Fig. 3 is a front view of the discharging device shown in section in Fig. 1. Fig. 4 is a vertical section of a part of the apparatus on an enlarged scale 40 and taken as on the line $x x$, Fig. 2, or $y y$, Fig. 5. Fig. 5 is a front view of a portion of the apparatus shown in Fig. 4, the bottom of the casing being removed and parts being in section. Figs. 6, 7, and 8 are detail views 45 hereinafter more fully described.

A is a zigzag casing or chute of any suitable height, the various bends of which are placed at a suitable angle to secure the free descent therein by gravity of the material to 50 be treated. I have found that in treating

grain an inclination of fifty-five degrees from the horizontal gives very good results.

A' A² is the frame-work supporting the apparatus, which latter may, as shown on the drawings, be partly supported by the various floors of the building within which it is erected.

B B are a series of heating-pipes, which are arranged parallel one to the other, as seen in Fig. 2, and follow the zigzag course of the 60 casing A, being by preference placed about midway between its upper and lower walls, as in Fig. 4. The pipes thus offer a large amount of heating-surface to the descending material, which is presented to them in comparatively thin streams or layers. The pipes are supplied with either steam or hot water, which (when steam is employed) enters, by preference, at their upper ends, as at b, Figs. 1 and 2, their lower ends being connected 65 with a tank C, partly filled with water. The steam is discharged into the water near the bottom of the tank, and that part which remains uncondensed rises to the top of the tank and is thence conducted to a steam-trap 70 C' by the pipe C², or it may be discharged direct into the atmosphere from the tank. I find that by permitting the steam to discharge into the tank C instead of directly into the steam-trap I am enabled to obtain a more 75 uniform distribution of the steam in the several pipes. Pressure-gages may be provided at suitable points on the pipes B and tank C, and valves may also be provided for regulating the flow of the steam or hot water 80 in the pipes and to some extent the temperature in the casing. The pipes B are retained in position by sockets D, Figs. 4, 5, and 6, secured to the upper walls of the casing, as by set-screws d, so that the material has a perfectly free passage along the lower walls of 85 the casing. The necks d' of the sockets and also the sides of the sockets themselves are beveled or rounded off to a thin edge, as shown, in order to offer as little resistance as 90 possible to the descending material. This method of mounting the pipes also enables the latter to expand or contract freely in a longitudinal direction.

E E are ventilating-trunks, which are con- 100

nected by a main trunk E' with an exhaust-
ing device, such as a fan. The trunks E fol-
low approximately the zigzag course of the
casing and are connected therewith by a se-
ries of cross-pipes E², which are each open to
the casing throughout their entire length, as
seen in Figs. 4 and 5. It will be observed
that the cross-pipes E² communicate by open-
ings E³ with the upper sides of the various
bends of the casing. This arrangement has
a double advantage—first, there is no lia-
bility of the material entering the cross-pipes
E², so that the openings E³ of said pipes may
be unobstructed, perforated shields being
quite unnecessary; secondly, the descending
stream of material as it passes along the va-
rious bends has both sides exposed alternately
to the ventilating-openings, and this greatly
facilitates the drawing off of the vapor.

20 A suitable valve or valves, as E⁴, is or are
provided at a convenient point or points for
the purpose of controlling and distributing
the flow of the mixed air and vapor in the
various trunks.

25 Fresh air is admitted into the casing by
means of the openings F on the upper walls
thereof, the said openings being provided
with coamings G, Figs. 4, 5, and 7, which pro-
ject a considerable way into the casing, so as
30 to lead the air into the body of the material.
The coamings G are tapered more or less to-
ward their upper ends, as shown, so that they
offer little resistance to the descent of the
material. They serve further to subdivide
35 or break up the stream of material, so that
the air-currents may act upon it with greater
effect, and so that it may be brought into more
intimate contact with the heating-tubes. For
a similar purpose I also provide other tapered
40 coamings or double diaphragms H, Figs. 4, 5,
and 8, placed intermediate to the coamings
G. The coamings H are by preference placed
directly below the cross-pipes E², so that the
vapor is drawn from the stream of material
45 while in its broken or subdivided state. To
still further assist the drawing off of the va-
por, the coamings H are perforated, as shown,
and thus form a series of perforated ventilat-
ing-tubes projecting into the casing. The
50 size and arrangement of the perforations in
the coamings are preferably such that the
material cannot readily enter the coamings
and choke them.

55 It will be obvious that the angles formed at
the various bends of the casing need not
necessarily be acute, as shown in the draw-
ing. They may be rounded to a greater or
less extent, so that the contour of the casing
approaches more or less to that of a sinuous
60 line.

65 The material to be treated is placed in or
supplied to a hopper J, provided with any
suitable adjustable feed device. Thence it
descends by gravity in thin streams or lay-
ers through the zigzag-casing A to the dis-
charge-chute K, being thoroughly dried in its
descent by the joint action of the heating-

70 pipes and the currents of air drawn into the
casing through the openings F and out
through the openings E³. The chute K may
be of any ordinary description. When fill-
ing into bags, however, I prefer to provide it
75 with two discharge-nozzles k k', each adapted
to discharge into one bag. A shutter k², piv-
oted at k³, midway between the nozzles, is
adapted to be drawn over to either side of
the chute by means of a cord k⁴, for the pur-
pose of closing either of the nozzles while a
full bag is being removed and an empty one
80 put in its place. An adjustable slide L is
also provided for regulating the discharge of
the material from the casing. I am aware
that a series of inclined plates or boards has
been mounted within a casing or housing and
the material dried in passing over these
85 plates or boards, and to such constructions I
make no claim.

I declare that what I claim is—

1. The combination, with an inclined chute
down which the material may descend by 90°
gravity, said chute having air-admission ori-
fices in its upper walls and heating-surfaces
in contact with the descending material, of
vapor-pipes communicating on the one hand
with an exhaust device and on the other hand 95
with the upper sides of said chute at points
intermediate to the aforesaid orifices, sub-
stantially as described.

2. The combination, with the zigzag chute
A, having air-admission orifices F in its upper 100
walls and vapor-exits E³ intermediate thereto,
and the heating-pipes B, of the tapered coamings
G, surrounding said admission-orifices
and projecting inward between the heating-
pipes, substantially as and for the purposes 105
described.

3. In a desiccating-machine, the combina-
tion, with an inclined chute having inlet-open-
ings and outlet-openings arranged alternately
in its upper walls and having internal heat-
ing-surfaces, with which the material de-
scending the chute is brought into contact, of
wedge-shaped coamings located below said in-
let and outlet openings and projecting for a
110 considerable distance into the chute with
their narrow ends facing the descending
stream of material, substantially as described.

4. The combination, with the zigzag chute
A, having inlet-openings F and outlet-openings E³, arranged alternately, as described, and 115
the heating-tubes B, of the tapered coamings
G H, projecting between the pipes and lo-
cated below the openings F E³, respectively,
and having their narrow ends facing the de-
scending stream of material, substantially as 120
and for the purposes described.

5. In combination with the zigzag chute A
and the heating-pipes B, passing down the
center thereof, the pipe-sockets D and the ta-
pered coamings G H, the said coamings and 125
sockets being all attached to the upper walls
of the various bends of the chute, whereby
each side of the stream of material is alter-
nately broken up and permitted to descend

without impediment, substantially as described.

6. The combination, with an inclined chute having internal heating-surfaces, as described, and a series of eduction-pipes opening into its upper walls, of a series of narrow perforated ventilating-coamings projecting into said chute and communicating with said eduction-pipes, substantially as and for the purposes described.

7. In combination with the zigzag chute A, the heating-pipes B, and the eduction-pipes E², a series of perforated ventilating-coamings H, communicating with said eduction-

pipes and projecting into the chute between 15 the heating-pipes, the said coamings being formed narrow with tapering upper ends, whereby they serve to break up the descending stream of material while offering a minimum amount of resistance thereto, substantially as described. 20

In testimony whereof I have signed my name to this specification in the presence of two subscribing witnesses.

CHARLES MALLINSON.
